DESIGN FOR A COMBINED LADY'S HAND-BAG AND VANITY CASE

Josefine Gierden, Köln-Nippes, Germany

Application December 9, 1936, Serial No. 66,411
In Germany May 25, 1936

Term of patent 7 years

To all whom it may concern:

Be it known that I, Josefine Gierden, a citizen of the German Republic, residing at Köln-Nippes, Germany, have invented a new, original, and ornamental Design for a Combined Lady's Handbag and Vanity Case, of which the following is a specification, reference being had to the accompanying drawing, forming part thereof.

Fig. 1 is a side elevational view of a combined lady's handbag and vanity case in closed position showing my new design;

Fig. 2 is a side elevational view thereof in open position, and

Fig. 3 is a front elevational view thereof in closed position.

The drawing shows a combined lady's handbag and vanity case comprising a bipartite bag, circular in front elevation, a circular vanity case, concentrically embodied therein, a bipartite locking device substantially circular in front elevation and substantially oval in side elevation and a handle attached to one part of the locking device.

I claim:

The ornamental design for a combined lady's handbag and vanity case substantially as shown and described.

JOSEFINE GIERDEN.
